CLAIM

The ornamental design for a cup with integrated folding lid as shown and described.

DESCRIPTION

FIG. 1 is a front perspective view of a cup with integrated folding lid according to our new design, in a folded configuration;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top elevation view thereof;

FIG. 7 is a bottom plan view thereof; and,

FIG. 8 is a front perspective view thereof in an unfolded configuration.

The dash-dash broken lines in the drawings illustrate portions of the cup with integrated folding lid that form no part of the claimed design. The dash-dot-dash broken lines represent bounds of the claimed design and form no part thereof.
